METHOD OF AND COMPOSITION FOR
REJUVENATING FABRICSGeorge M. Babcock, deceased, late of Evanston,
Ill., by Bilia Babcock, administratrix, Evanston,
Ill.No Drawing. Application June 29, 1931,
Serial No. 547,783

2 Claims. (Cl. 26—28)

This invention relates to a method of and composition for rejuvenating fabrics, such as woolen and silk cloth, and its purpose is to provide a method and process by which fabrics which have 5 been worn shiny may be rejuvenated and caused to assume their original appearance and texture. It is a well known fact that suits of clothing and other articles formed of woolen or silk cloth become shiny after continued use so that it is 10 often necessary to discard them because of their unattractive appearance long before they have been worn out. Heretofore there has been no satisfactory method of overcoming this difficulty and eliminating the objectionable shine. The 15 principal object of the present invention is to provide a new composition of matter which may be applied to the fabric with the result that the shiny appearance is removed, the nap is restored to its original condition and the dye is renewed 20 or redistributed in such a way that the fabric has a new and freshened appearance. In practicing the invention, the new composition of matter is applied over the surface of the cloth or fabric and is then rubbed in order to secure uniform distribution thereof and the penetration 25 thereof into the fibres of the cloth or fabric, thus causing each unit of area of the cloth or fabric to be restored substantially to its original state after a very short period of rubbing and a very 30 limited application of the compound. In practicing the method, the rubbing of the cloth or fabric is preferably effected by an object made up of an improved composition of matter hereinafter disclosed which also forms a part of the 35 present invention and which is adapted to expedite the rejuvenating operation and to bring about more satisfactory results. The nature of the improved method of the present invention and of the improved composition, as well as the 40 character of the object employed for rubbing, will appear more fully hereinafter.

The cloth or fabric to be rejuvenated is preferably spread out over a flat surface and the composition of the present invention is applied over 45 the surface of the cloth, preferably by spraying, so that a substantially uniform distribution of the solution is brought about. This composition is in the form of a solution which is made up of the following ingredients, which are preferably 50 combined in the following proportions and added

to each other in the order in which they are stated, as follows:

Industrial grain alcohol	16 fluid ounces
Ammonia, 24% strength	3 fluid ounces
Glacial acetic acid, 99% strength	4 fluid ounces
Muriatic acid, 18% strength	1 gram
Oil of lavender	1½ grams
Chloroform	2 fluid ounces

After the foregoing ingredients have been 10 added to each other in the order stated and thoroughly mixed, sufficient distilled water is added thereto to make up a total volume of one gallon, which may then be bottled and is ready for distribution to the trade.

After the foregoing composition of matter has 15 been spread or otherwise applied to the surface of the cloth to be renewed, the cloth is preferably rubbed for a short period of time in order to bring about a more perfect distribution of the 20 composition and cause the composition to penetrate the fabric to some extent. This results in the restoration of the original nap of the cloth with a removal of the shine and an apparent partial dissolution and redistribution of the dye, so 25 that the cloth takes on a more lively appearance and resembles very closely a fabric of the same character and quality which has not been used.

It has been found that the results obtained 30 with the use of the foregoing composition of matter are substantially improved if the rubbing of the cloth is effected by means of a small briquette made up of rubber having embedded therein a quantity of powdered pumice stone and powdered emery. The pumice stone and emery are distributed through the rubber while it is in a more or less plastic state and then the rubber is vulcanized under high pressure, for example, a pressure of 18,000 pounds per square inch, with the 35 result that there is finally formed a body of material which may be employed advantageously in carrying out the process of the present invention. The rubber compound is preferably vulcanized in small molds to form briquettes which may be conveniently engaged by the hand of the user for rubbing purposes and the rubbing surface of the briquette may preferably be rough, 40 although that is not essential.

The most perfect results are obtained by using 45 all of the ingredients of the foregoing composition

combined in the proportions stated but some advantageous results may be obtained by using portions only of these ingredients combined in other proportions and the present invention is not limited except by the scope of the appended claims.

What is claimed is:

1. A composition of matter for rejuvenating cloth made up of grain alcohol, ammonia, glacial acetic acid, muriatic acid, oil of lavender and chloroform.
- 10 2. A composition of matter for rejuvenating

cloth made up of sixteen fluid ounces of grain alcohol, three fluid ounces of 24% strength ammonia, four fluid ounces of 99% strength glacial acetic acid, one gram of 18% strength muriatic acid, one and one-half grams of oil of lavender and two fluid ounces of chloroform mixed together and added to sufficient distilled water to make up a total volume of one gallon.

5

BULLIA BABCOCK, 10
Administrator of the Estate of George M. Babcock, Deceased.
